UNITED STATES PATENT OFFICE

HENRY BOOT, OF PHILADELPHIA, PENNSYLVANIA, ASSIGNOR TO THOMAS DOLAN & CO., OF SAME PLACE.

DESIGN FOR NUBIA.

Specification forming part of Design No. **6,778**, dated July 22, 1873; application filed June 28, 1873.

C.

To all whom it may concern:

Be it known that I, HENRY BOOT, of Philadelphia, Pennsylvania, have invented a Design for Nubia, of which the following is a specification:

The principal feature of my design for a nubia, which is illustrated by the figure in the accompanying drawing, is the groundwork or body A of the fabric. This is of a checkered pattern throughout, it consisting of alternate squares *a* and *b*, the former composed of open-knitted loops or meshes, and the latter of loops of a different character closely interlocked, the whole presenting the peculiar and pleasing effect represented. Upon this ornamental body is a stripe or stripes, B, and at

the edge of the same a border, D, both composed of scalloped threads coarser than and interlocked with those of the said body.

Irrespective of the colors employed, I claim—

1. The design for the body or groundwork A of the nubia, substantially as described and represented.

2. The design for the whole nubia, including the body A, stripe B, and border D.

In testimony whereof I have signed my name to this specification in the presence of two subscribing witnesses.

HENRY BOOT.
